UNITED STATES PATENT OFFICE.

CHARLES O. RYBERG, OF BROCKTON, MASSACHUSETTS.

FABRIC FOR MATS, &c.

1,160,201.

Specification of Letters Patent.

Patented Nov. 16, 1915.

Application filed March 23, 1915. Serial No. 16,459.

To all whom it may concern:

Be it known that I, CHARLES O. RYBERG, a citizen of the United States, and resident of Brockton, in the county of Plymouth and State of Massachusetts, have invented certain new and useful Improvements in Fabric for Mats, &c., of which the following is a specification.

My invention has for its object to enable relatively small waste pieces of sole leather, or other like material, which constitutes waste residue left after cutting out the material into larger parts or pieces, to be utilized as the body of a fabric which may be flat and suitable for use as a floor mat, or tubular and suitable for use as the body of a basket.

The invention further has for its object not only to utilize material such as that above mentioned, but also to enable it to be incorporated into a fabric at the minimum cost of time and labor.

The invention consists in the improvements which I will now proceed to describe and claim.

Of the accompanying drawings forming a part of this specification: Figure 1 represents a side or top view of a flat fabric or mat embodying my invention; Figs. 2 and 3 represent respectively end and edge views of the same; Fig. 4 represents a section on line 4—4 of Fig. 1; Figs. 5 and 6 represent side views respectively of one of the body blocks and one of the filling blocks hereinafter referred to; Figs. 7 and 8 represent side views of two of the bridging ties; Fig. 9 represents a side view of one of the coupling ties; Fig. 10 represents a view illustrative of the method of making the flat fabric shown by the preceding figures; and Fig. 11 represents an end view of a tubular fabric embodying the invention.

The same reference characters indicate the same or similar parts in all the views.

In making the fabric of my invention, I proceed as follows: The leading ends of a series of wires or wire rods 12 of indeterminate length are assembled side by side and parallel with each other, said rods being suitably spaced apart, as shown by Fig. 10. Said leading ends are adapted to be moved forward from time to time as the building up of the fabric progresses, the reserve wire from which the supply is drawn being preferably disposed in coils 12^a mounted at a

suitable distance from the point where the building operation is performed, the coils being adapted to rotate and deliver the wire as required. The extremities of the wire rods 12 are bent inwardly from the dotted line position to the full line position represented by Fig. 10, said ends being united at 13 by a brazing operation, or otherwise, so that the united ends form the end members of the closed frames 1, 2, 3, 4, 5, hereinafter described. I next proceed to assemble on the rods 12 body blocks 14, bridging ties 15, and coupling ties 16. The body blocks 14 are cut from waste pieces of sole leather, or other like material, and each block has open slots 17 formed in its opposite ends, said slots extending lengthwise of the blocks, as indicated by Fig. 5. The first blocks supplied are inserted between the side members of the frames and bear on the connected end portions of the rods 12. I next apply another series of blocks in staggered relation to the blocks first applied, the last mentioned blocks occupying the spaces between contiguous frames and being in staggered relation to the blocks first applied. I proceed in this order until a fabric of the desired width has been built up, and then sever the rods 12 at a suitable point between their outer ends and the source of supply, leaving portions of the rods projecting from one edge of the fabric, and bending said portions inwardly and uniting them at 13^a to complete the frames 1, 2, 3, 4, 5. The length of the blocks 14 and the distance between the inner ends of their slots 17 is such that said inner ends abut against the wire rods 12, the open slots enabling the blocks to be assembled on the rods, while the latter are connected with the source of supply, or in other words, are of indeterminate length, the blocks being engageable with the rods either by inserting them in inclined positions between adjacent rods and then moving them to horizontal positions, or by deflecting the wires or increasing the distance between them at suitable points between the connected leading ends of the wires and the source of supply to enable the blocks to be inserted horizontally between the deflected portions of the wires and then moved to place in the fabric without being inclined. It will be seen that the described relative arrangement of the blocks is such that each frame confines a series or row of blocks 110

which are spaced apart and alternate with other rows of blocks which occupy the spaces between contiguous frames.

During the above described operation I apply at suitable points bridging ties 15 which connect the longitudinal members of each frame and prevent the frame from spreading, and coupling ties 16 of the same construction which connect the adjacent members of contiguous frames, and hold the frames at the predetermined distance from each other. Each of said ties is composed of a length of wire of smaller gage than the wires 12, so that the ties are adapted to be interposed between adjacent blocks without causing a noticeable separation of said blocks. Each tie is bent to form hooks, as shown by Figs. 7, 8 and 9, the bends of the hooks bearing on the wire rods 12. The ties are adapted to be assembled on rods 12 of intermediate length, their hooks being formed by bending the wire after it has been located on the rods 12. The wire of the ties may originally have its end portions at right angles with its body portion, as indicated by dotted lines in Figs. 7 and 8. It will be understood that each tie is incorporated in the fabric by being placed against the exposed sides of the blocks 14 during the operation of assembling the blocks, each tie after being located being covered by blocks next applied.

The construction thus far described may be endless or tubular, as shown by Fig. 11, a tubular structure thus far described being suitable for various purposes, such as the bodies of waste baskets. When a tubular structure is produced, the wires 12 and the coils from which they are drawn will preferably be arranged in a circular series, the operation of building up the fabric being as above described.

When the invention is embodied in a flat fabric I complete the ends of the fabric in the manner next described. The outer ends of the blocks 14, which are confined by the end frames 1 and 5, are separated from each other by spaces. I fill these spaces and make the ends of the fabric practically continuous by inserting relatively short filling blocks 14^a between the outer ends of the elongated blocks 14 confined by the end frames, said filling blocks being of the same material as the blocks 14 and provided at their inner ends with slots 17^a corresponding in form to the slots 17 in the blocks 14, and receiving the outer members of the end frames. In the outer ends of the filling blocks 14^a are relatively shallow slots or grooves 20, which are in alignment with the slots 17 in the outer ends of the blocks 14. Along each end of the fabric is extended a binding wire rod 21 which is of the same size as the rods 12 and may be drawn from a coil 12^a, as indicated by Fig.

10. The leading end 21^a of the binding wire 21 is bent inwardly against an edge of the fabric, as indicated by Figs. 1 and 2. The binding wire occupies the coinciding grooves 20 and slots 17 of the blocks 14 and 14^a, and is confined by bridging ties 15^a, which have the same construction and function as the bridging ties 15 but are made longer than the latter, as shown by comparison of Figs. 7 and 8. The bridging ties 15^a are long enough to bridge the space between the binding wire 21 and the inner longitudinal member of the end frame. The ties 15^a therefore act through the spacing blocks 14^a on the outer longitudinal members of the end frames to prevent the spreading of said frames.

For convenience of description and identification, I apply the term "edges" to the top and bottom margins of the structure shown by Fig. 1, and the term "ends" to the right and left vertical margins of said structure. It is obvious that the number of the closed wire frames is not limited to the number here shown.

Having described my invention, I claim:

1. A fabric composed of spaced-apart wire rods, body blocks having open longitudinally extending slots in their end portions, whereby the blocks may be assembled on rods of indeterminate length, the rods extending through the slots and being united in pairs at opposite edges of the fabric to form a series of independent closed frames confining rows of spaced-apart blocks, the adjacent members of contiguous frames confining other rows of spaced-apart blocks the ends of which alternate with the ends of the blocks confined by the frames, hooked wire bridging ties connecting the members of each frame and preventing the spreading of the frames, and hooked wire coupling ties coupling together the adjacent members of contiguous frames, said bridging and coupling ties being composed of flexible wire adapted to be bent during the assembling operation to form rod-engaging hooks, so that the ties may be assembled on rods of indeterminate length.

2. A fabric composed of spaced-apart wire rods, elongated body blocks having open longitudinally extending slots in their end portions, whereby the blocks may be assembled on rods of indeterminate length, the rods extending through the slots and being united in pairs at opposite edges of the fabric to form a series of independent closed frames confining rows of spaced-apart blocks, the adjacent members of contiguous frames confining other rows of spaced-apart blocks the ends of which alternate with the ends of the blocks confined by the frames, relatively short filling blocks occupying the spaces between the outer ends of the elongated blocks confined by the end frames and

slotted at their inner and outer ends, wire binding rods extending along the ends of the fabric and extending through the slots in the outer ends of the said elongated and filling blocks, said binding rods being secured at opposite edges of the fabric, the filling blocks being adapted to be assembled on frame rods and binding rods of indeterminate length, hooked wire bridging ties 10 connecting the members of each frame, the bridging ties at opposite ends of the fabric being elongated and engaged with the binding wires and with the inner members of the end frames, and not only preventing outward deflection of the binding wires, but 15 also acting through the filling blocks to pre-

vent the spreading of the end frames, and hooked wire coupling ties coupling together the adjacent members of contiguous frames, said bridging and coupling ties being composed of flexible wire adapted to be bent during the assembling operation to form rod-engaging hooks, so that the ties may be assembled on rods of indeterminate length.

20

In testimony whereof I have affixed my signature, in presence of two witnesses.
